Attorney

UNITED STATES PATENT OFFICE.

HARRY WILKE, OF DENVER, COLORADO.

SIGNAL DEVICE FOR ROAD-VEHICLES.

1,248,229.

Specification of Letters Patent. Patented Nov. 27, 1917.

Application filed December 21, 1915. Serial No. 62,055.

To all whom it may concern:

Be it known that I, HARRY WILKE, a citizen of the United States, and a resident of Denver, in the county of Denver and State of Colorado, have invented certain new and useful Improvements in Signal Devices for Road-Vehicles, of which the following is a specification.

My invention relates to signaling devices, and it is the object thereof to provide simple and convenient means by which the driver of a vehicle may indicate to others, whether behind or ahead of his vehicle, his intention to turn to one side or the other. My invention is particularly intended for convenient attachment to motor-vehicles, for use in cities and wherever road traffic is in any way congested. Minor objects of my invention relate to the specific structural features thereof, and will be more fully set forth hereinafter.

In the accompanying drawings Figure 1 is a rear view of a device embodying my invention, as applied on an ordinary type of wind-shield on a motor-vehicle, Fig. 2 is a detail showing a part of the device in longitudinal vertical section, Fig. 3 is a detail horizontal section through the central part of the casing-tube, Fig. 4 is a transverse section on the plane of the line $x-x$ of Fig. 3, Fig. 5 is a partial plan view showing in detail the attaching device for the casing-tube, and Fig. 6 is a transverse section of the casing-tube, showing the attaching device in side elevation.

In carrying out my invention I provide a tubular casing 1 formed by a piece of metal pipe or tubing of suitable length and diameter. In one side of the tube there is a longitudinally extending slot which at its center is offset circumferentially of the tube so that when the tube is disposed horizontally there are, in effect, two horizontal slot-portions whose adjacent ends are connected by a short vertical slot-portion. The tube may be provided with flaring mouth-pieces 2, if desired, to give the ends thereof a finished appearance. Within the central part of the tube a cylindrical block 3 is disposed slidably, and into said block is screwed the stem 4 of a handle 5, said stem extending through the slot in the side of the tube, so that by means of the handle the block may be moved longitudinally. To said slideable block 3 is connected a two-part rod or staff which extends longitudinally within the casing and carries at each

of its ends an expandable signal device, the same being adapted to project and open from the end of the tube when the handle 5 is moved toward the respective end from a central position with respect to the longitudinal slot in the casing. Preferably the two parts of said rod or staff are each made from a single piece of wire, of which the central portion is formed into a loop 6, the portions 7 adjoining said loop being twisted together, and other small loops or eyes 8 being formed at intervals by opening out the convolutions of the twisted portions, as shown clearly in Fig. 2. Besides the expanded portions forming the eyes 8, there is a larger expanded portion 9 of which the size is such that it is normally wider than the diameter of the tube, and which thus frictionally engages the walls of the tube when inclosed thereby. At the outer end of the twisted portions 7 each side of the wire is formed into a small coil 10, and from said coils the two end-portions of the wire extend as normally divergent arms 11 which are provided at their ends with loops or eyes 12. To said eyes 12 and the coils 10 are secured the corners 13 and 14 of a small triangular flag 15 made of fabric or other flexible material.

The inner ends of the two rod or staff parts, each formed as above described, extend into the tubular bore of the center-block 3, being in overlapped relation to each other so that the two end-loops 6 coincide as shown in Fig. 3, or so that any two of the eyes 8, or one of said eyes 8 and one of the end-loops 6 coincide. The stem 4, extending through said coincident loops or eyes, connects the two parts of the staff in adjusted relations to each other and to the center-block 3.

When the device is in use the casing is secured in a horizontal position on a suitable portion of the vehicle, as to the lower portion of the wind-shield A, as shown in Fig. 1, so that the handle 5 may be conveniently reached by the driver. The length of the tubular casing is made such that the ends thereof will extend out transversely of the vehicle, far enough for the signal flags when projecting therefrom to be distinctly seen by the driver of a vehicle approaching from behind, as well as by any person in front of the vehicle on which the signal is displayed. As the width of the various vehicles to which the signal might be applied varies within certain limits, it

2

is preferable in practice to make the casing-tube long enough for use on the widest vehicle. Then, when applying the device to a narrower vehicle, the ends of the tube 5 may be cut off to the desired length, the mouth-pieces 2, of course, being removed and replaced upon the ends of the tube after the same is shortened. After shortening the casing-tube, the effective length of the 10 flag-staff may be adjusted by overlapping the ends of the two parts and connecting them by passing the stem 4 through the eyes or loops thereof, as before mentioned. The length of the staff is made such that 15 both signal-flags will be drawn into and inclosed by the tube when the handle and the stem 4 are at the center, or offset part, of the longitudinal slot in the side of the casing. When the tube is shortened all of 20 the reduction of its length may be made at one end, thus causing the center of the longitudinal slot to be not coincident with the center of the casing, should such a location of the handle be desired in order to 25 have it closer to and in more convenient reach of the driver. When all shortening of the tube is done at one end, the adjustment in length of the staff will also be made entirely by changing the relation of 30 one of the staff-parts to the center-block.

For connecting the casing-tube with a wind-shield, as in Fig. 1, I provide a pair of clamping devices, each having an annular body 16 through which the tube is 35 passed, and a hook-portion 17 adapted to engage the frame of the wind-shield as shown in Figs. 5 and 6, the clamps being secured to the tube and the latter held firmly against said frame by small set- 40 screws 18.

From the foregoing the operation of the signals will be apparent. The coils 10 form springs which enable the divergent arms 11 to close inwardly as they are drawn into the 45 casing-tube, the flags 15 becoming gathered into folds at the same time, so that the entire flag device is readily contained within the tube, and will assume its expanded position instantly upon being pushed out of the 50 end of the casing. The expanded staff-portions 9, by frictionally engaging the walls of the tube, tend to hold the staff in any position to which it may be moved, and to prevent looseness and rattling of the parts 55 when the vehicle is in motion. The offset at the center of the longitudinal slot serves to mark the central position of the handle 5, at which the signal-flags are both in the retracted or concealed position. Said offset of the slot also serves to form a stop for the handle when either of the flags is withdrawn from the displayed position, preventing the handle from being moved directly

far enough to cause the other flag to be displayed; it being obvious that in moving 65 the handle from one end of the slot to the other it is necessary to pause momentarily at the center while the stem 4 is moved vertically through the offset part of the slot.

Now, having described my invention, 70 what I claim and desire to secure by Letters Patent is:

1. In a signal device for road vehicles, the combination with a tubular casing having a longitudinal slot in one side thereof, of a two-part staff extending longitudinally within the casing, signal members carried at the ends of said staff and adapted to be projected beyond the ends of the casing by movement of the staff longitudinally, and a 80 member connecting the parts of the staff in an overlapped adjusted relation, said member extending outside the casing through the longitudinal slot therein.

2. In a signal device for road vehicles, 85 the combination with a tubular casing, of a two-part staff slidable longitudinally within the casing, signal members carried at the ends of the staff and adapted to be projected beyond the ends of the casing by 90 longitudinal movement of the staff, each part of the staff being formed of a twisted wire having the convolutions thereof expanded to form eyes, and means adapted to pass through said eyes of the staff-parts to 95 connect said parts in adjusted relations to each other.

3. In a signal device for road vehicles, a tubular casing, a two-part staff inclosed thereby, each part of said staff comprising 100 a wire having an eye at one end, portions adjoining said eye twisted together, parts expanded from said twisted portions to form additional eyes, parts at the other ends of said twisted portions coiled to form 105 springs, and arms normally extending divergently from the coiled portions, flags secured to said arms so as to be spread out when the arms are in divergent position, means for connecting the eye staff-parts in 110 adjusted relations to each other, and means for moving the staff to protect the arm-portions and flags from the ends of the casing.

4. In a signal device for road vehicles, a tubular casing, a staff movable longitudinally within the casing, expansible signal members carried at the ends of the staff and adapted to be projected from the ends of the casing to display the same, the staff consisting of wires having portions twisted 120 together and having parts of the convolutions of the twisted portions expanded to frictionally engage the walls of the casing, and means connected with the staff for moving the same to display the signal members. 125

HARRY WILKE.
